INVENTOR

BY *Frank M. Slough*,
ATTORNEY.

UNITED STATES PATENT OFFICE

ALBERT SHAROWSKY, OF CLEVELAND, OHIO, ASSIGNOR OF ONE-HALF TO JOHN H. SHARP, OF DETROIT, MICHIGAN

ALARM CIRCUIT CLOSING SWITCH

Application filed November 19, 1928. Serial No. 220,359.

My invention relates to alarms and relates more particularly to an electric alarm adapted to be used on a cash drawer, desk, showcases, or the like.

5 An object of my invention is to provide an improved mechanical switch for closing an electrical circuit to ring an alarm at a remote point.

Another object of my invention is to provide an alarm which may be rendered inoperative by a secret switch.

Another object of my invention is to provide an alarm for a cash drawer or the like which may be readily attached without mutilating the article to which it is attached.

Another object of my invention is to provide a device of the class described which is easy and economical to construct.

Still other objects of my invention and the invention itself will become apparent from the following description of the drawings which form a part of this specification, and wherein,

Fig. 1 is a fragmentary plan view of the mechanism as installed showing diagrammatically an electrical circuit therefor;

Fig. 2 is a fragmentary elevational view of certain parts of the device, the housing, therefor being shown in section;

Referring now to the drawings wherein like parts are designated by like reference characters; at 1 I show a fragment of the side of a desk adjacent a drawer 2, the drawer being of the kind adapted to slide inward and outward to gain access thereto. Secured to the side of the drawer, by screws 5, is a rack bar 3, which is provided with a pair of teeth 4 that extend toward the switch mechanism.

A switch mechanism, adapted to be operated by the rack, is secured to the body of the desk, and comprises a shallow metallic housing or box 6 provided with a lid 7 held thereon by screws 8. Within the housing are disposed a gear element 9 and a gear lever ele-
ment 10.

The gear element 9 comprises a relatively large toothed portion 11 which in this instance is shown as having four teeth, and a relatively small spur gear 12 which is axially aligned and secured to the larger portion by rivets.

The spur gear 12 is in mesh with a gear 13 which supports a lever 14. The lever 14 is adapted to oscillate a link 18, the lever being secured to the gear by rivets. The link is preferably provided with a pair of clevises 40 and 41 at each end and the intermediate portion 42 is constructed of fibre or like non-conductive material.

Both of the gear elements are mounted upon short shafts 15 and 16 which are rotatably journaled in the walls of the housing. Spacing washers 17 may be applied on the shafts adjacent the sides of the gears to space the same from the housing. The element 9 being so positioned in the housing adjacent the side that the enlarged toothed portion 11 extends beyond the sides of the housing through an aperture therein.

The lever 14 is pivotally secured to the end of the connecting link 18, the other end of the link being connected to the blade 19 of a knife switch 20. The knife switch comprises an insulated block 31, secured to the box by screws 32, and supports a pair of contacts 21 and 22 substantially as shown. The switch blade is pivotally secured to the contact 22 and is adapted to oscillate into and out of contact with the contact 21, to close and open an electrical circuit.

When the drawer 2 is pulled out, the enlarged toothed portion 11 of the element 9 engage the teeth 4 on the stationary rack 3, which rotates the teeth about the pivot 15, and the gear 12 is rotated therewith in a clockwise direction. There being but two teeth on the rack they contact with the teeth 4 for but a short space thus limiting the amount of rotation of the gear 12. Rotation of the gear 12 in a clockwise direction causes the gear 13 to be rotated in a counterclockwise direction and it carries with it the lever 14.

The lever arm being rotated toward the switch 20, forces the switch blade 19, by means of the connecting link 18, into contact with the contact 21, closing the circuit. The circuit comprises an annunciator 23, a source of current 24, which may be the ordinary house current or a battery, and a manually operated switch 25; all the elements being

connected in series as shown. The leads 26 and 27 are connected to the contacts 21 and 22 of the switch 20.

Assuming that the manuel switch 25 is closed, operation of the drawer will cause the circuit to be closed, by the switch 20, operating the annunciator 23.

When it is desired to open the drawer, without the operation of the annunciator; 10 the switch 25, which may be disposed in a concealed place, is opened; thus the operation of the switch 20 does not close the circuit and the annunciator will not operate.

In this particular embodiment of my invention, I have shown the rack as being attached to the side of the drawer and the switch box as being attached to the desk. It might be advisable however, to reverse the 15 two and attach the rack to the desk and the switch to the body of the drawer; in either event the operation of the device would be the same.

The annunciator shown is the ordinary bell, but a light or other indicating means 20 may be substituted therefor with like results. The two gear elements are shown as being made in two parts riveted together, but it is also within the purview of my invention to make the elements in one piece.

Having thus described my invention in an embodiment thereof I am aware that numerous and extensive departures may be made therefrom, but without departing from the spirit of my invention.

I claim:

1. In an alarm device for an article of furniture having a reciprocable drawer, a movable switch element, a rotary element for operating the same, a connection between the 40 rotary element and the switch element, means for rotating the rotary element, said means comprising a rotary gear element and a longitudinally reciprocable rack element associated with a drawer of the article of furniture and movable into and out of meshed relation with the gear element.

2. In an alarm device for an article of furniture having a reciprocable drawer, a rack secured to the drawer, a rotary toothed element engageable and disengageable by the rack upon alternate movements of the drawer and rotatable thereby, a rotary switch operating element rotated by the rotary element, a movable switch member and a connection between the second rotary element and the switch member.

3. In an alarm device for an article of furniture having a reciprocable drawer, a longitudinally movable rack secured to the 60 drawer, a rotary toothed element engageable and disengageable by the rack and rotatable thereby, a rotary switch operated element rotated by the rotary element, a movable switch member and a connection between the second rotary element and the switch member,

whereby rotary movement of the second rotatable member in one direction may close the switch.

4. In an alarm device for an article of furniture having a reciprocable drawer, a movable switch element, a rotary element for operating the same, a connection between the rotary element and the switch element, means for rotating the rotary element, said means comprising a rotary gear element and gear 75 rotating means associated with the drawer of the article of furniture and movable into and out of meshed relation with the gear element upon reciprocatory movement of the drawer.

In testimony whereof I hereunto affix my signature.

ALBERT SHAROWSKY.
